Atty.

UNITED STATES PATENT OFFICE.

VERNON McDOWELL, OF RICHMOND, VIRGINIA.

WINDOW-SASH LOCK.

1,355,403.

Specification of Letters Patent. Patented Oct. 12, 1920.

Application filed December 20, 1919. Serial No. 346,276.

To all whom it may concern:

Be it known that I, VERNON McDOWELL, a citizen of the United States, residing at Richmond, in the county of Henrico and 5 State of Virginia, have invented new and useful Improvements in Window - Sash Locks, of which the following is a specification.

This invention relates to window sash locks, and has for one of its principal objects, the provision of a lock which can be manufactured and sold at a nominal cost, and one which can be readily and easily applied to the window to effectively prevent 15 raising of the lower sash.

Another important characteristic of the invention, resides in the fact that the locking element is automatically operable, in that it is spring pressed to assume an active position when the lower sash of the window is moved to a closed position.

In carrying out the invention, I also provide means for limiting the movement of the locking element under the action of the 25 spring to its active position, the construction and arrangement of parts being such that the locking element can be readily and easily removed to its inactive position when it is desired to raise the lower sash without any 30 binding between the component parts of the lock.

Other objects and advantages will appear when the following detail description is read in connection with the accompanying drawings, the invention residing in the construction, combination and arrangement of parts 35 as claimed.

In the drawing forming part of this specification like numerals of reference indicate 40 similar parts in the several views and wherein:

Figure 1 is a fragmentary front elevation of a window showing the lock applied thereto.

Fig. 2 is a sectional view through the window showing the lock in elevation and in position to lock the window sash against movement.

Fig. 3 is a vertical sectional view through 50 the window and lock showing the inactive position of the window, and the lower sash partly elevated.

Fig. 4 is a front elevation of the locking element.

Fig. 5 is a similar view of the spring therefor.

Referring to the drawings in detail, 10 indicates the upper sash of the window, the lower sash being indicated at 11. The lock forming the subject matter of my invention 60 comprises a locking element 12, which is preferably in the form of an elongated member hinged as at 13 for outward swinging movement from the attaching plate 14 which is provided with openings 15 for the reception 65 of suitable fastening elements 16 utilized in securing the lock in a vertical position upon one side rail of the upper sash 10. By reason of the hinged connection with the attaching plate 14, the locking element 70 12 is capable of assuming a position indicated in Fig. 2, wherein the lower end of the locking element overlies the adjacent rail of the lower sash to prevent the sash from being elevated. The locking element is 75 given this position through the instrumentality of a spring 17 of a shape corresponding to the shape of the locking element 12 or slightly shorter than the latter. The spring 17 is provided with openings 18 adapted to 80 register with the openings 15 of the locking element, so that the same fastening elements 16 utilized in securing the locking element in position are passed through the openings 18 to maintain the spring interposed 85 between the locking element and the side rail of the sash 10 as shown in Figs. 2 and 3. The spring is tensioned to normally maintain the locking element in its active 90 position, and to limit the outward movement of the locking element 12 under the influence of the spring 17, I provide a substantially L-shaped plate 19 which I have secured in any suitable manner, upon the upper edge of the adjacent rail of the lower 95 sash 11. The locking element 12 at an appropriate point in its length is provided with an elongated slot 20 through which projects a lug or finger engaging member 21 formed on the spring 17 by locking the 100 latter as at 22 and bending the material separated by the slot in the manner shown in Fig. 3. The purpose of this lug will be hereinafter described. The lower edge of the slot 20 formed in the locking element 12, 105 is bent rearwardly as at 23 to provide an abutment for the adjacent or lower edge of the spring 17, the parts being in active position as shown in Fig. 2. This position permits the lower edge of the spring 17 to rest 110 upon the abutment 23, an arrangement which prohibits the locking element 12 from

being moved to an inactive position, until after the spring 17 is moved from the abutment 23. When it is desired to unlock the window, and allow the lower sash to be elevated, the thumb or finger of the operator is pressed against the lug 21, which projects an appreciable distance through the slot 20 as shown in Fig. 2. In this manner, the spring 17, is moved independently of the locking element 12, until the spring is separated from the abutment 23, and upon further movement of the thumb or finger the locking element 12 is moved to its inactive position in close proximity to the side rail of the sash 10. The parts are held in this position until the lower sash of the window is slightly elevated in the manner shown in Fig. 3, in which position the lower sash serves to hold the locking element in its inactive position. In order that the lower sash may pass the hinged joint 13 of the locking element, the upper rail of the lower sash is cut away for a short distance as at 24. In order to prevent the spring 17 from binding against the abutment 23, when the lug 21 is pressed against to release the lower sash, I provide an auxiliary spring 25 which assists in separating said parts. This spring 25 forms an integral part of the spring 17, being in the nature of a strip defined by cutting the body of the spring in the manner illustrated, this spring 25 being slightly curved to bear against the adjacent side of the locking element 12. Manifestly when the parts are arranged in the position illustrated in Fig. 2, the spring 25 is placed under tension so that when pressure is brought to bear against the lug 21, it assists in moving the spring 17 out of engagement with the abutment 23. The lock in its entirety is extremely simple in construction, and in addition to being very efficient for the purpose intended can be manufactured and marketed at a nominal cost.

While it is believed that from the foregoing description the nature and advantages of the invention will be readily apparent, I desire to have it understood that what is herein shown and described is merely illustrative, that I do not limit myself in this connection, and that such changes may be resorted to when desired as fall within the scope of what is claimed. 50

Having thus described my invention what I claim as new is:— 55

1. A window sash lock comprising a locking element pivotally mounted upon the upper sash, a spring interposed between the sash and said element to normally project the latter above the adjacent rail of the lower sash, an abutment carried by the element and adapted to be engaged by the free end of the spring whereby said element is maintained in active position, means carried by the lower sash to limit the outward movement of the element under the influence of the spring, said element having a slot and a finger engaging member carried by the spring and projecting through said slot 65 as and for the purpose specified. 70

2. A window sash lock comprising a hinged locking element mounted upon the sash, a spring interposed between said element and sash and operating to normally project said element above the adjacent rail of the lower sash, means carried by the rail of the lower sash, to limit the outward movement of said element, an abutment carried by said element for engagement with the lower end of the spring to hold said parts fixed relatively in active position, said element having a slot, a finger engaging member carried by the spring and projecting through the slot to effect the release of said 80 sash, by moving said spring and locking element away from said abutment. 85

In testimony whereof I affix my signature.

VERNON McDOWELL.
